(57) **CLAIM**

The ornamental design for a light fixture, as shown and described.

DESCRIPTION

FIG. 1 is a perspective view of a first embodiment of the light fixture of the present design;
FIG. 2 is a front elevation view thereof;
FIG. 3 is a top plan view thereof;
FIG. 4 is a bottom plan view thereof;
FIG. 5 is a right side elevation view thereof;
FIG. 6 is a rear elevation view thereof;
FIG. 7 is a left side elevation view thereof; and,
FIG. 8 is a perspective view of a second embodiment smaller in size than the first embodiment.
The broken lines in the figures are for illustrative purposes only and form no part of the claimed invention.
